PHOTOGRAPH VIEWER

Philip Bieber, Coral Gables, Fla., and Jerome V. O'Grady,
Freeport, N. Y.

Application January 12, 1955, Serial No. 33,954

Term of patent 14 years

(Cl. D61—1)

FIG. 2

Figure 1 is a side elevational view of a photographic viewer showing our new design; and Figure 2 is a front elevational view thereof. The sides of the viewer not shown are plain.

We claim:

The ornamental design for a photograph viewer, substantially as shown and described.
